6 Claims. (Cl. 250—39)

The present invention relates to frequency indicators utilizing tubes wherein gases under reduced pressure are caused to become luminous. It is known in the prior art, for instance, in 5 Lecher wire systems, that radio frequency electromagnetic oscillations may be indicated by means of luminous actions merely by bringing the two current supply leads (electrodes) of a Geissler tube or a similar gas-filled tube or vessel in contact with the two Lecher wires placed in pairs parallel to each other, the gas confined inside the tube being caused to become luminescent by the action of electromagnetic waves fed by bilateral electrode leads. It is also 10 known in the prior art that a strong radio frequency electromagnetic field may be indicated and revealed by tubelets filled with a rare gas such as helium, without an electrode being in actual contact with a part carrying the oscillations. This mode of indication was effective 15 in cases where the electromagnetic field was strong enough to cause luminescence of the gas enclosed in the vessel also outside the conducting parts. However, whenever the electromagnetic fields are weak and not sufficiently intense, the luminous actions are not capable of being produced, while an arrangement carrying radio frequency energy is generally unsuited to cause 20 excitation of luminescence with two-electrode luminous tubes. In fact, such an arrangement may essentially be used only when working with 25 waves of a length of an order of magnitude comparable with the dimensions of the apparatus, so that there are caused to exist pairs of points 30 on the apparatus which have opposite potentials whereby there are produced short circuits through pairs of electrodes with the connected luminous tubes.

In other words, an arrangement of the sort known in the prior art was useful only for oscillations which, compared with the apparatus, may not be regarded any longer as quasi-stationary. However, all technically or commercially important radio frequency oscillations involve quasi-stationary working conditions so 35 that the use of this known method is precluded alone for this reason.

It has also been suggested in the prior art (luminous quartz crystal method of Giebe and Scheibe) to have recourse to piezo-electric crystals for the detection of electrical oscillations of a definite frequency which operates as a resonator in a rarefied rare gas atmosphere, the rare gas being caused to luminesce at points 40 where the quartz crystal presents potential anti-

nodes. It has also been found (by Eberhard) that in order to produce luminous actions it is not necessary, when using a quartz resonator, to directly introduce the crystal into the rare gas atmosphere, indeed, that under definite presuppositions and conditions it is sufficient that the quartz crystal should be disposed outside the vessel in the immediate vicinity of the glass wall of the vessel filled with the rare gas atmosphere. In fact, with such an arrangement it is even 10 feasible to arrange one of the electrodes by which the quartz is caused to oscillate, with the oscillations in turn producing luminescence of the gas. To be sure, this scheme requires that the crystal be ground to a certain thickness in 15 order to be responsive to a definite wave length, but it was otherwise not adaptable enough to permit of its further uses. At any rate, in this arrangement only those parts of the rare gas atmosphere were caused to luminesce which were 20 located in the direct neighborhood of the quartz, to be more precise, directly at the glass wall, and this means an impairment of the chances for observing luminous actions of the type here 25 dealt with.

Now, the present invention obviates the disadvantages of such a known arrangement, and is adapted to indicate and detect radio frequency oscillations of relatively low energy or power by rendering these oscillations perceptible by lum- 30 inous actions.

According to the invention, a conductive part of the circuit arrangement which carries radio frequency oscillations is in single pole connection with a closed transparent container or vessel containing vapors or gases adapted to be rendered luminescent by radio frequency oscillations. Such single pole connection may consist of a short wire or lead, the latter, however, is made 35 so short in length that an adequately large amplitude is introduced into the gas filled vessel. The latter may consist, for instance, of a glow discharge (gaseous-conduction) lamp or tube equipped with a pair of helical or loop-shaped electrodes, the vessel being filled with neon or a 40 neon-helium mixture. Of the two current supply leads of a standard glow discharge lamp the outer one is connected by means of a short and relatively stout copper wire of a few centimeters 45 length to a point of the circuit arrangement which is a potential nodal point for the radio frequency oscillations. Suited for this purpose is a point in the circuit arrangement which is not grounded and which in reference to the ground presents as 50 high as possible a resistance; for example, in the 55

case of a wave generator the end of the grid condenser connected with the grid of the tube. In contrast to arrangements known in the earlier art (Lecher wires) where for the operation of the scheme the existence of two points of opposite potential changing in their potential at a high rate of frequency was the prerequisite condition, actual experiments have shown that with the use of suitable luminous tubes a luminous action is producible even when the rare gas vessel is connected with a single point of the circuits presenting marked amplitude fluctuations of the radio frequency energy. At first blush this appears surprising in that the determination of the electric potential save for one constant is arbitrary, and as it is wholly feasible to make this constant dependent upon time. Hence, it is possible to regard the ground as a constant potential and to consider the radio frequency oscillations of a conductor part in relation to the said ground potential; but it would be just as well to regard these conductor parts being insulated from the ground as being at constant potential, and to speak comparatively of radio frequency oscillations of the grounded parts. Although this latter mode of looking at the situation is not conventional or customary it would nevertheless be justified from a physical viewpoint. Hence, it would at first not be plausible for what reasons, in the case of single pole connection of the luminous vessel with the circuits, a luminous phenomenon should arise just when the parts insulated against earth are united with the tube in one pole. It is this feature that distinguishes the present idea from a two-pole circuit scheme known in the prior art, for instance, in the use of Lecher wires in which, independently of the selection of the datum or reference point for making the potential measurements, there exists a potential fluctuation between the two electrodes occurring at high frequency. However, experimentation shows that, quite surprisingly, under conditions as before stated, also a single pole connection suffices for obtaining luminosity.

An a posteriori explanation the inventor believes to be as follows: While the luminous tube is only in single pole connection with the circuit arrangement, to be more precise, with the part thereof which is insulated from ground, the other parts of the luminous tube, i. e., the electrode positioned opposite the other pole, other metallic parts, etc., however, are inductively acted upon by the ground potential for the reason that in the inductive actions the larger mass of the surrounding (ambient) parts being at earth or other stationary potential predominates compared with the relatively feeble inductive actions from the conductor parts insulated from the ground and possibly in single pole connection with the glow discharge vessel. Hence, even if one were to assume the viewpoint that the potential of such insulated parts is to be regarded as constant, and correspondingly the earth potential, the potential of the wires, etc., as varying at a high frequency, then also those parts of the glow discharge tube which are in single pole connection with the insulated circuit point would have to be regarded as being at a constant potential. However, owing to the said inductive actions from the grounded parts the opposite metal parts or other metal parts present inside the glow discharge tube and not in conductive relationship with the enclosed electrode would undergo inductive radio frequency potential variations. In other words, no matter how the situation be viewed, i. e., for every

choice of the zero potential (including one subject to time variation) radio frequency electromagnetic oscillations between the conductor parts of the luminous tube must be expected in an arrangement according to the invention involving single pole connection, with the result that the gas is luminesced as the experiment has evidenced.

Among the points of the circuit arrangement insulated from ground where a single pole tube connection should most preferably be effected there are to be recommended particularly such points of the circuits where, by the aid of special auxiliary means, high potential amplitudes are obtainable. What may be particularly recommended for this object are piezo-electric crystals existent in the wave generation scheme for the purpose of frequency stabilization. Compared with luminous resonators known in the prior art, the present invention, quite apart from the constructional arrangement of the quartz (which in the present scheme is not so restricted as to its arrangement as is true of luminous resonators) distinguishes itself inter alia owing to the fact that the invention is useful also in connection with oscillators. Whereas in resonators it is only certain and definite points of the quartz that give rise to luminosity in the neighboring gases, while other points of the quartz will not participate in this phenomenon, any desired point of an adequately insulated electrode of the quartz may be united with the luminous vessel or tube in order to cause the latter to luminesce, while the other electrode will not manifest a luminous action or will luminesce only to a far slighter degree even if it is insulated though not to the same extent.

The idea underlying this invention is schematically illustrated in the accompanying drawings wherein Figures 1 and 2 are shown by way of example. Figs. 3 and 4 illustrate other embodiments utilizing the present invention.

Figure 1 shows a wave generating circuit arrangement, wherein it is proposed to indicate the generated waves by a luminous action. Referring to Figure 1, 1 denotes a triode transmitter comprising a filament 2, a grid 3 and a plate 4. The heating of the filament 2 is effected from a battery 5; the plate circuit contains a plate potential source 6, and between the latter and the plate 4 is provided a tuned oscillation circuit comprising a coil 7 and a rotary condenser 8. Between the grid 3 and the filament 2 is disposed a quartz crystal oscillator comprising a crystal 9, the coat 10 on the grid end and the coat 11 on the filament end. The plate potential source is shunted or bridged by a condenser 12. The grid coat 10 of the crystal 9 is united by a short and stout copper wire 13 with one pole 15 of a neon glow-discharge lamp 14, where-as the other pole is left unconnected. If the other pole of the gaseous-conduction lamp is associated with the filament end coat 11 of the quartz crystal oscillator, there arise also luminous actions, to be sure; but by the glow discharge lamp there is set up a resistance, though of high ohmage, between the coats 10 and 11 of the quartz crystal oscillator adapted to diminish the ensuing amplitudes.

Figure 2 shows the arrangement of the quartz and the luminescent tube drawn to a somewhat larger scale in section. To be sure, it is possible to unite the crystal coat directly with the luminescent tube by way of a short wire; but it is sufficient if of the two plug pins 19 and 16 whereby

the crystal oscillator is secured in the circuit, the one on the grid end indicated at 19 is united with the metal wire 13, or if the terminal pin 17 brought to the grid of the transmitter valve is connected with the luminous tube by way of a short metallic wire. A conductive sheath or envelope laid around the glass vessel such as an external tin foil coat 18 tends to enhance the luminous phenomena inasmuch as it increases 10 the inductive actions from the outside. For the same reason it is recommendable to dispose the inner electrode-lead near the glass walls in direct proximity to the conductive sheath.

The invention has been tried out in the presence of circuit elements having, e. g., the following dimensions. What was used was a quadratic quartz plate 9 possessing a natural period of 100 m (thickness about 0.9 mm). The oscillation circuit 7, 8 consisted of a coil comprising 20 10 spires and a frequency-proportional rotary condenser of a maximum value of 500 cm. The shunting condenser 12 was of 1 mfd. Instead of an oscillator tube or transmitted valve it was sufficient to use a simple receiver tube RE604 25 or else RE134 (manufactured by Telefunken). The same was operated with a 4-V accumulator 5 for the filament and a plate potential 6 derived from a normal network supply and having a potential between 110 and 270 V according to 30 the current. Oscillating occurs on setting condenser 8 turned an angle over 60 degrees. Beyond this point the oscillations break off suddenly (at 63 and 67 degrees, respectively), the plate current as a result rises very markedly, 35 being 42 and 23 millamps, respectively, for the two tubes, whereas in the resonance setting of the oscillatory state is amounted to only 5.3 and 1.5 millamps, this minimum of the plate current value arising in the presence of a condenser position of 61 and 64 degrees, respectively. Upon further reduction of the condenser value 8, the plate current exhibits another rise in accordance 40 with the departure of the natural period of the oscillation circuit 7, 8, from the natural frequency of the quartz crystal 9.

The luminous tube, when using the same copper connection wire of 3 cm. length and the tube RE134 lights up only when the condenser is in the resonance position at about 60 degrees. 50 When employing tube RE604, the glow discharge tube luminesces also at all lower positions of the condenser. Hence, the invention makes it feasible to indicate resonance both by the arising of a potential crest and exact resonance as well as in the presence of a region characterized by increased potential variations, independently of the particular point involved. By lengthening the copper wire brought to the glow discharge lamp it is possible to damp the radio frequency oscillations to a point so that also when using tube RE604 luminescence of the gas will happen only when the condenser is set in the resonance position.

This condition arises when the connecting wire 65 is lengthened to about 25—35 cm.; both slender copper wire as well as radio frequency stranded wire (litzendraht) has been found suited for the purposes of establishing the said connection. Hence, according to the invention it is possible to 70 influence and control the damping of the radio frequency lead by choosing corresponding dimensions for the length of the supply lead. Inasmuch as it is possible to choose a length as great as 30 cm. which is considerable for radio frequency circuit schemes it is possible in practicing

the invention to use and connect the glow discharge lamp at any desired point in the scheme without any particular limitations being imposed.

In contrast with the luminous resonator types disclosed in the earlier art which operate only in the direct neighborhood of the piezo-electric crystal, the arrangement of this invention allows of a great deal of freedom as regards the disposition of the lamp or tube. For instance, in practicing the invention there is no inconvenience in mounting one of the glow discharge tubes outside the apparatus, the latter containing the assembly of the circuits, to thus indicate the oscillatory state of the same. The arrangement is useful not only for self-excited transmitters, 15 but also for separately excited transmitters as well as receiver sets, and it may also be employed for the purpose of functioning as a signalling means or the like to indicate the presence of oscillations of a definite frequency. For instance, 20 a luminous device of the kind here disclosed may be used for controlling a telephone or a loudspeaker to show whether oscillations are present at all in case the telephone or loudspeaker fails to indicate oscillations. It is also possible in case 25 of non-use of the loudspeaker or headset to cut this lamp in circuit in order to save current (the consumption by the glow discharge lamp being extremely small) or else to prevent fatiguing due to the constant carrying of the headset of tele- 30 graphic operators and the like. By the use of the invention it is also possible to dispose upon a common switch panel for different transmitters and receivers and other apparatus carrying radio frequency oscillations, controlling means, supervisor 35 lamps, etc. for the various apparatus provided that, in the presence of a plurality of apparatus, the necessary shortening of wires is taken into consideration. The glow discharge lamp thus excited, because of its low consumption, may also 40 be used directly for illuminating purposes.

One embodiment of such a check-up or supervising equipment is schematically shown in Figures 3 and 4. Figure 3 shows an arrangement comprising two transmitters which are to be 45 checked up as regards their state of oscillation by a comprehensive lamp device. Figure 4 is a view of a suitable switch panel.

Referring to Figure 3, suppose S_1 and S_2 are two transmitters which by the aid of a corresponding 50 quartz crystal Q_1 and Q_2 , respectively, are to be maintained at a certain transmitter frequency. In each of the transmitters S_1 and S_2 the grid end coat of the crystal Q_1 and Q_2 , respectively, is in conductive relationship with two glow 55 discharge or gaseous-conduction lamps G_{11} and G_{12} for the transmitter S_1 , and G_{21} and G_{22} for the transmitter S_2 . Of these the pair of glow discharge tubes, the ones first named, i. e., glow discharge lamps G_{11} and G_{12} have a short connection 60 lead to the coupling electrode of the crystal; and the other one pair, i. e., the glow discharge lamp G_{21} and G_{22} , a longer lead. The envelopes of these lamps consisting of a conductive coat is indicated in Figure 3 by two parallel lines, and 65 in the elevation Figure 4 by a double circle. By choosing different dimensions for the supply leads, say, for the lamps G_{11} and G_{12} for the transmitter S_1 , it is possible to insure the following conditions:

Each length of the connecting wire corresponds to a definite threshold value of the oscillation amplitude; and it is only when the amplitude of the oscillations at the connected quartz crystal coat exceed this threshold value that the glow 70

discharge lamp will flash up. By choosing different threshold values which is easily accomplishable by a corresponding alteration of the length of the lead or connecting wire it is possible to insure several advantages, it having to be noted in this connection that it is possible to use more than two different glow discharge lamps, that is to say, more than two threshold values for one transmitter for the purpose of indication, etc.

A piezo-electric crystal, as is well known, serves for the stabilization of the wave generated by an oscillator insofar as the frequency of this wave, under the influence of the crystal, becomes equal to the natural period or one of the natural periods of the quartz crystal whenever the natural period of an oscillation circuit provided in the transmitter exercising a frequency-governing effect exhibits certain deviations from the natural period of the crystal. An oscillation circuit in the transmitter consisting, for instance, of a condenser and inductance coils, under the action of quite a number of external agencies, such as the temperature, atmospheric pressure, mechanical percussions of the apparatus, and so on, is very apt to experience changes in its natural period. It is well known also that an alteration of resistance in the oscillation circuit may occasion not only damping, but under certain circumstances also a change in the natural period of this particular circuit. In all of such cases where, under the influence of uncontrollable and inadvertent changes of the oscillation circuit quantities the natural period of the circuit undergoes alterations, or if under the influence of intentional or anticipated changes in damping (caused, e. g., indirectly by modulation or the like) there occurs thus a disturbing change in the natural period, recourse may be had, as is well known in the art, to the use of a wave stabilizing piezo-electric crystal, which in its own motion is relatively little impeded by outside agencies, and which in addition may be provided extensively with special ways and means in order that such slight influences as may exist may be precluded, for instance, by accommodating the crystal inside an ambient independent of the temperature, thermostats or melting ice or inside a pressure-independent ambient or confinement in vacuo or the like. To be sure, these auxiliaries insure that within certain limits, i. e., as long as the departures of the frequency of the oscillation circuit from the natural period of the crystal keep inside a certain easily insurable limit, the frequency of the wave will be constant and equal to the natural period of the quartz crystal.

But the amplitude of this oscillation nevertheless will be dependent upon the difference between the natural frequency of the quartz crystal and the natural period of the oscillation circuit or circuits co-determinative in the frequency of the oscillation.

Hence, the situation may arise that, on relying upon the frequency-stabilizing action of the oscillator crystal such fluctuations as are ascribable to or producible by temperature fluctuations or the like in the natural periods of the oscillation circuit or circuits are wholly neglected or at least not fully appreciated, with the result that in the course of a gradual temperature change the amplitude of the oscillation is subjected to considerable variations and liable to fall appreciably below the desired or attainable value.

Now, this troublesome occurrence may be

counter-acted, for instance, by an arrangement as shown in Figures 3 and 4. With this end in view it may be advisable to choose the lead of one of the glow discharge tubes, e. g., G_{11} to the crystal so short in length that relatively low amplitudes of the oscillations will occasion luminescence of the glow discharge tube. Hence, this particular glow discharge tube will make it possible to tell whether oscillations are present at all. Hence, the glow discharge tube G_{11} , when arranged as shown in Figures 1 and 2, would be caused to luminesce provided that the setting of the rotary condenser 8 lies somewhere between 63 and 67 degrees. It is only when this limit has been exceeded, i. e., when the oscillations are broken off entirely and when the considerably larger emission current corresponding to the static characteristic flows through the tube, that the glow discharge tube G_{11} would cease luminescing. Of course, the said tube or lamp will fail to luminesce at all when the generator is not in circuit. The second glow discharge tube G_{12} on the other hand has a connecting wire brought to the crystal Q_1 of such a length that only in the neighborhood of the real resonance position will this glow discharge tube be caused to luminesce, i. e., when the amplitude of the generated wave is equal to the desired maximum or at least in its direct neighborhood, in other words, in the example illustrated in Figure 1 and Figure 2 in the presence of a condenser position of 61 and 64 degrees, respectively.

If on the panel Figure 4 no glow discharge tube is caused to flash up at all this goes to indicate that the transmitter does not oscillate at all or at least not at appreciable amplitude. If solely lamp G_{11} luminesces, but not tube G_{12} , this must be interpreted to mean that the transmitter is oscillating, but with an unduly weak amplitude. This may mean that disconnection should be effected. A differential photometer or the like may be so set that it will be caused to respond when one of the glow discharge lamps, i. e., lamp G_{11} is caused to luminesce, and not the other one, G_{12} , whereby a signal device in the operator's room is actuated whence the reason for the failure of the desired amplitude being produced is ascertained. The reason, inter alia, may be that one of the tuning means has experienced an unintended mechanical shift. In most instances, however, the setting of the tuning elements may have remained constant, though the value thereof may have been affected or changed by external agencies such as temperature fluctuations and the like. On the panel Figure 4 is thus shown below the glow discharge lamps G_{12} and G_{22} a vernier setting means A_1 and A_2 , respectively, say, for a condenser by the aid of which readjustment is accomplishable, so that the respective glow discharge lamp G_{12} or G_{22} , as the case may be, is caused to reluminesce. On the panel Figure 4 there is furthermore shown below the glow discharge lamps G_{11} and G_{21} a switch E_1 and E_2 , respectively, which is used for connecting the entire transmitter assembly. In the place thereof there could also be provided an indicator device such as a glow lamp or the like to show whether the transmitter is in circuit or not. When the same is connected, but when the glow discharge lamp G_{11} or G_{21} indicates the absence of waves, this means that the transmitter is out of order, for instance, on account of the fact that the natural period of the oscillation circuit has so much changed in one direction that the oscillations have been broken off. In the embodiment

Figure 1 this would happen upon a change in the sense of increased capacity or reduced natural frequency of the circuit.

The arrangement as hereinbefore disclosed is not confined to the special embodiments here described in connection with the transmitter. In fact, the invention may be used, e. g., with receivers, resonator crystals, etc. in schemes which may be superior to the luminous crystals resonators. In the case of the luminous resonator, the presence of the luminous action is the criterion for very sharp frequency coincidence. The result is that whenever there occurs a comparatively slight frequency change, the crystal will fail to luminesce any more. Hence, it is not feasible to ascertain from the quartz crystal itself whether oscillations exist at all; and after this has been ascertained by some other ways and means, whether the wave length is too great or too small. In previous practice one remedy of the situation has been to use a plurality of luminous crystals, say, three or five, of which the middle one had a natural frequency the same as the desired frequency, whereas the other crystals had a natural period slightly differing therefrom, for instance, with equal distances between the natural waves of these luminous crystals. However, even in such a scheme it has been found quite often that no luminescence was produced, and there was no other way out of the difficulty than to reset, detune, or the like, in order to get into one of those very small or narrow resonance ranges inside which one of the luminous crystals would flash up. Hence, it was often enough only possible after a makeshift detuning to determine whether oscillations existed at all, and then ascertain by observations as to which one of the various crystals would luminesce to thus determine the sense of the departure or detuning. These difficulties are obviated also by the present invention. In fact, by the use of the invention, and the provision of a correspondingly long supply lead or wire and a suitable metallic sheath or electrode shape it is possible to choose the range inside which the glow discharge lamp, in the presence of oscillations of the crystal or other circuit point carrying wave amplitudes, will be caused to luminesce. But if also smaller amplitudes acting at the crystal coat are to be ascertained, all that is necessary with that end in view is to choose the wire to the glow discharge tube correspondingly shorter.

I claim:

1. An arrangement for indicating radio frequency oscillations of low power comprising a gas filled glow tube having a transparent, hermetically sealed envelope containing gas therein and which is adapted to exhibit luminous phenomena, a wire within said envelope, a conducting band adjacent said envelope and insulatingly positioned with respect to said wire, a source of radio frequency oscillations of low power, and an electrical connection from said source to said wire, said band being physically separated from and not connected to said source, the length of said connection determining the threshold value of the amplitude of the oscillation which it is desired to detect.

2. An arrangement for indicating high fre-

quency oscillations comprising a gas filled, transparent, hermetically sealed envelope adapted to exhibit luminous phenomena, a wire within said envelope connected to a terminal outside said envelope, an external band of tinfoil surrounding said envelope, adjacent thereto, and insulatingly positioned with respect to said wire, an oscillation generator comprising an electron discharge device having a cathode, a control electrode, and a piezo-electric crystal located between said control electrode and the cathode, and a connection between said wire and that side of said piezo-electric crystal which is connected to the control electrode of said electron discharge device, the length of said connection determining the threshold value of the amplitude of the oscillations which it is desired to indicate.

3. An arrangement for indicating radio frequency oscillations of low power comprising a plurality of gas filled glow tubes each of which comprises a hermetically sealed envelope having a wire therein and extending externally thereof, and a conducting band adjacent each of said envelopes and insulatingly positioned with respect to its associated wire, a piezo-electric crystal resonator having a plurality of electrodes, and individual connections of predetermined lengths from one of said electrodes to the wires of said glow tubes, the striking of the glow in said tubes being determined by the lengths of said individual connections, said conducting bands being separated from and not connected to any of the circuit elements of said arrangement.

4. An arrangement for indicating radio frequency oscillations of low power comprising a glow tube having a hermetically sealed envelope, a wire within said envelope extending externally thereof, a circular conducting band adjacent said envelope and insulatingly positioned with respect to said wire, a piezo-electric crystal having a plurality of electrodes and a connection from one of said electrodes to said wire, said connection being of predetermined length and the only one from said glow tube to the circuit elements of said arrangement, the length of said connection determining the threshold value of the amplitude of the oscillations which it is desired to indicate.

5. An arrangement as defined in claim 4, characterized in this, that said individual connections have different lengths.

6. An arrangement for indicating high frequency oscillations comprising a hermetically sealed glow tube which is adapted to exhibit luminous phenomena, a wire within said tube, a conducting band adjacent the envelope of said tube and insulatingly positioned with respect to said wire, a second similarly constructed glow tube, a source of high frequency oscillations, and individual electrical connections of predetermined different lengths from said source to the wires of said respective tubes, the conducting bands of said tubes being physically separated from and not connected to said source, the lengths of said connections being such that said first glow tube indicates the production of oscillations in said source, and said second glow tube indicates the attainment of a predetermined amplitude of the oscillations in said source.

OTTO EMERSLEBEN.
